[57] **ABSTRACT**

A thrust producing gas turbine adapted for aircraft propulsion at both moderate and especially high thrust values, and characterized by intermittent explosive burning of fuel into the working fluid and the directing thereof into an impulse turbine for the partial absorption of energy by means of a decrease in velocity and for the conservation of pressure for continued and subsequent effective burning. The engine embodiment comprises a compressor section followed by a nozzle-burner section shaped for the explosive high pressure high velocity discharge of working fluid into the turbine section for the absorption of operating energy and conservation of pressure, and through which the working fluid exhausts through stator blades that reestablish axial flow and thrust; the working fluid completing its combustion and/or being injected with fuel for efficient after-burning. The compressor air is stratified as it passes through the nozzle-burner section for cooling effect and to supply the products of combustion for supporting complete primary and secondary burning.

REACTION MOTOR EMPLOYING
INTERMITTENT EXPLOSIVE COMBUSTION AND
IMPULSE TURBINE

BACKGROUND

The practice of jet propulsion involves the "action equals reaction" principle and momentum or the "quantity of motion" defined as the product of the mass of a body and its velocity or $M = mv$; m being mass and v being velocity. The gas-turbine engine as it is employed for purposes of jet propulsion involves these principles wherein the air intake condition is mv_1^2 and the exhaust condition is mv_2^2 ; all as a result of energy being applied by combustible fuels and operation of fluid dynamics dependent upon the energy transfer between a working fluid and a rotor.

Internal combustion jet engines are characterized by convergent and divergent fluid flow passages embodied sequentially in a compressor section, a combustion section, and a turbine section; it being a general object to provide thrust as efficiently as possible, or a difference in mass velocity between the intake and exhaust of the engine. Although many variations of turbine design have been employed in aircraft propulsion, the velocity turbine is employed exclusively to absorb operating energy from the working fluid, characterized by nozzles and expansion blading and consequent increased velocity with a corresponding drop in pressure as the working fluid moves rearward therethrough. Conventional jet turbines are therefore comprised of stationary blades or nozzles through which the working fluid expands before flowing through the rotor blades which react and which may also be an expansive nozzle or nozzles; stage by stage as circumstances require. Such a velocity-reaction turbine is to be distinguished from the pure impulse-reaction turbine with which this invention is particularly concerned and wherein the working fluid arrives at the nozzle entrance with the approach velocity C_2V called the "carry-over velocity" in multistage turbines in the first stage of which C_2V is so small that it may be neglected and the fluid may be assumed to start from rest. Significantly however, velocity is reduced commensurate with energy absorption while P_1 (entry pressure P_1) at the nozzle discharge into the bucket or moving blade is conserved through the reaction function of turning or redirecting the working fluid, and to the end that $P_2 = P_1$ (outlet pressure P_2) at the discharge from said buckets or moving blades. And it is the turning and/or redirection and the phenomenon that $P_2 = P_1$ which is advantageously employed in practicing my invention as hereinafter disclosed.

Fluid dynamics, especially when involved with explosive forces, involves what has become known as the "Munroe effect" by which expanding gases are focused, so to speak, for efficient control over the work to be performed thereby. In practice, explosive charges are directed by means of this principle, either by shaping the charge or the chamber from which it is to emanate. Similarly, it is an object of this invention to shape the nozzle section divergently for a most forceful impingement or high velocity contact of the working fluid upon the turbine blades; bearing in mind that it is the advantageous effect of momentum which is of primary concern, and that high pressure P and high velocity V are the controlling factors of efficient turbine operation.

Heat control is an important factor in the operation of internal combustion jet engines, there being various ways to limit the temperature of the working fluid as it passes through the turbine blading. For example, only 5 part of the compressed air is passed through the burner cans of the conventional jet engine, the remainder passing therearound to restrict the temperature of the working fluid to a value that the turbine blading will withstand; and part of the air flow is bypassed, as for 10 instance fan-jet engines. In this regard, it is an object of this invention to separate the flow of working fluid within the nozzle section of a jet engine or gas-turbine. With this invention, the nozzle section is comprised of rearwardly divergent annular burners arranged concentrically one within the other with an annular coolant duct therebetween.

Maximum thrust from jet engines is most often derived from "after-burning", which is wasteful with conventional engines utilizing velocity-reaction turbines 20 having lowered exhaust pressures. It has been long recognized that high pressures are required for efficient burning of fuel, and conventional turbine engines are sufficiently efficient only within the turbine section and are necessarily deficient, for the reasons advanced 25 above, in the tail-pipe or exhaust section where after-burning occurs. Therefore, it is an object of this invention to provide a jet propulsion engine of the character thus far referred to that maintains high pressure in the tail-pipe or exhaust section, for efficient after-burning. 30 To this end, therefore, I have employed the impulse turbine wherein $P_2 = P_1$; the inlet and outlet pressures related as hereinabove set forth. Consequently, the tail-pipe pressure after the turbine is at an efficient value 35 nearly as great as the most efficient pressure preceding entry through the turbine blading.

Present day jet propulsion engines rely entirely upon the difference between M_1 and M_2 for thrust, as derived from increased velocity of the working fluid; simply an increase in velocity. In contradistinction, it is an 40 object of this invention to internally accelerate working fluid of reduced velocity thereby effecting the difference in momentum M . In this regard, the characteristics of the impulse turbine are used to advantage to change axial flow into a vector or helical flow and converting a portion of the working fluid energy into rotative power, and during which process the aircraft sees a substantial reduction in and/or to an extent no rearward thrust, and following which stator blading redirects the working fluid axially to restore axial thrust at 45 $P_2 = P_1$. It is to be understood that the initial directional change from axial to circumferential flow is less than 50 100 percent as the working fluid passes from the burner-nozzles and into the turbine blading. By reaction of the working fluid with impulse turbine blading, there is a redirecting of the working fluid with or without subsequent stator blading, and to the extent that the flow is directed circumferentially with a temporary negation 55 of forward thrust. However, by turbine blade design and/or by employing subsequent stator blading, the remaining working fluid energy is reestablished as axial thrust and conserved as a propulsive thrust. Thus propulsive thrust is maintained at a reduced velocity and high pressure commensurate with the energy remaining 60 in the working fluid after removing a portion of the energy as power.

Conventional jet propulsion turbine engines have continuous burning subject to "flame-out" and heat

dissipation problems, it being an object of this invention to provide highly efficient intermittently explosive high pressure burning ahead of the turbine and with coolant fluid admixed therewith so as to control nozzle temperature of the working fluid. With the present invention, intermittent fuel injection is provided within the confines of the divergent nozzle-burner section shaped so as to gain the Monroe effect, and combined with ignition means therefor; whereby high velocity accompanies said high pressure for thrusting the working fluid through the turbine blading. Still further, the impulse blading that I employ conserves the pressure as $P_2 = P_1$ for efficiently effective combustion aft of the turbine.

It is a general object of this invention to combine the aforementioned objectives into a coordinated concept referred to herein as an aero thrust engine or the like, and which follows accepted engineering principles for the most efficient operation thereof at both moderate and high thrust values.

DRAWINGS

The various objects and features of this invention will be fully understood from the following detailed description of the typical preferred form and application thereof, throughout which description reference is made to the accompanying drawings, in which:

FIG. 1 is a longitudinal sectional view illustrating an aero thrust engine embodying the features of the present invention.

FIG. 2 is an enlarged detailed sectional view of the nozzle-burner section of the engine shown in FIG. 1, and

FIG. 3 is an enlarged detailed section taken as indicated by line 3-3 of FIG. 2.

PREFERRED EMBODIMENT

The gas turbine engine of the present invention can take various forms in each or all of its three major sections; namely the compressor section X, the nozzle-burner section Y and the turbine section Z. Generally, the engine is of axial flow design wherein the intake condition is $mv1^2$, and wherein the exhaust condition is $mv2^2$. The compressor section involves means to pressurize the flow of working fluid therethrough and is characterized by a powered rotor, either of the centrifugal or axial flow type or a combination thereof, stator blading being provided as circumstances require in order to gain the desired axial or helical flow as may be necessary. The nozzle-burner section Y can vary according to the concept herein disclosed, characterized by its shape for the support of intermittent explosive combustion induced therein. In practice, the nozzles are established by stator blading disposed so as to direct the propulsive thrust axially with accelerating velocity as combustion occurs therein. The turbine section Z can also vary according to the concept herein disclosed, characterized by impulse blading or that type of turbine blading in which $P_2 = P_1$, there being a reduction in velocity as energy is absorbed to create operating power used to drive the rotor of the compressor section X and the various accessories as may be required.

Referring now to the drawings, I have shown an axial flow compressor section X that involves a plurality of stages of rotor and stator blades 10 and 11 that receive the intake air and reduce the volume thereof to in-

crease the pressure as it moves as working fluid therethrough. The flow passage 12 is an annulus of large capacity at the intake and of reduced capacity at the discharge into the nozzle-burner section Y. A rotor 13 carries the blades 10 while a stator 14 in the form of a case and frame carries the blades 11, there being bearings 15 that journal the rotor within the stator. It is to be understood that the compressor section X pressures the working fluid to the highest pressure permissible for the efficient primary and secondary burning to be subsequently accomplished, as will be described.

The nozzle-burner section Y forms an axial flow continuation of the compressor section, and in accordance with this invention utilizes the Munroe effect, so to speak, for accelerating the working fluid in order to increase velocity. The axial flow point at which P_1 is established may vary with engineering design, as it may be early at the juncture of discharge from the compressor section X into the nozzle-burner section Y, or it may be later at any point up to the release of working fluid into the turbine blades of turbine section Z. In any case, there is a point in the axial flow where P_1 is established preceding entry of the working fluid into and through the turbine blades.

In carrying out this invention, the burning of fuel in the working fluid is stratified for separation thereof from coolant fluid advantageously used for heat control and/or subsequent burning. Thus, there are at least two layers of working fluid, one concentrically disposed within the other in annular strata established by a diffuser. In the engine illustrated there is an outer burner strata 20 and an inner burner strata 21, in which case there is at least one diffuser ring. According to this invention, a portion of the working fluid is separated out as coolant and accordingly there is a pair of concentric diffuser rings 22 and 23 between which there is an intermediate coolant strata 24 which folds rearwardly with increased velocity during the explosive combustion. In the preferred form, therefore, the strata 20 and 21 are concentric cylinders of divergent conical form having interface engagement with strata 24 rearward of the diffuser rings 22 and 23, the strata 24 being of right cylinder form with the rings and of divergent cone-shape rearward thereof.

The diffuser rings 22 and 23 are shaped so as to focus the burning of fuel rearwardly, and they are characteristically divergent so as to induce the rearward expansion and acceleration of the working fluid. Accordingly, the strata 20 and 21 are of expanding cross section as they extend rearward, thereby to induce the expansive burning of fuel therein, the rings 22 and 23 terminating in sharp trailing edges substantially forward of the nozzle discharge immediately ahead of the turbine blading (see FIG. 2). Structural support for the diffuser rings 22 and 23 is provided by radial struts 19 also in the form of stator vanes advantageously formed with fluid directive walls and terminating in sharp trailing edges (see FIG. 2). In practice, a substantial portion of the nozzle-burner section Y is devoted to a burner chamber 25 for efficient directive explosion and for the comingling of gases whereby a cooling effect takes place or is initiated ahead of the turbine blading. By properly proportioning the amount of coolant, a continued cooling effect is produced within and for the protection of the turbine blading.

In accordance with this invention, regulatory fuel injection means and regulatory fuel ignition means are

provided for introducing energy into the working fluid. Each strata of working fluid designated for burning, such as layers 20 and 21, are provided with fuel injectors 26 indicated as nozzles, and from which fuel is intermittently supplied from a fuel pump means 27 and sprayed into the separated strata 20 and 21 respectively. The injectors 26 open into the strata 20 and 21 at either or both the inner and outer walls of the structure forming the same, and they are circumferentially disposed at a frequency commensurate with the density of fuel injection desired. In practice, the fuel injection means is located at the forward end of the annular passages formed by the diffuser rings 22 and 23.

The regulatory fuel ignition means is shown as one or more ignitors 30, such as spark or glow plugs, located rearward of the fuel injectors. That is, ignition follows injection, there being at least one ring of ignitors 30 rearward of each ring of injectors 26, and preferably a series of axially spaced rings of ignitors 30, 30', etc, adapted to progressively ignite the injected fuel. The rings of ignitors 30 are axially spaced as indicated and one ring thereof disposed so as to assume ignition within chamber 25.

In carrying out this invention, there is regulatory timed sequence (at intervals) of combustion by synchronizing the operation of means F and I in order to control power output by means of the frequency of explosions, each of which occurs at efficient pressure and velocity. The fuel is intermittently injected at timed intervals by distribution fuel pump means 27, there being any number of patterns of injection sequence dependent upon the number and arrangement of said injectors 26. And accordingly, the injected fuel charges are subsequently ignited by electrical discharge distributor means 28 of the ignition means I, timed so as to follow the injection with a spark or the like that is discharged for the intermittent ignition of the fuel charges, as they are injected.

The compressor section X and nozzle-burner section Y cooperate to provide intermittent explosive burning of fuel into the working fluid so as to increase the energy and the discharge of said working fluid into the turbine section Z at a high velocity and an efficient pressure. The velocity and resultant thrust can be varied as required, by controlling the amount of fuel injected, as by throttling or by frequency and duration of injection. Thus, the working fluid that moves intermediate the fuel charges and explosive burning thereof has a heat control effect; the intermediate strata of coolant 24 has its continuing heat control effect; and all to the end that working fluid temperature at the discharge of the nozzle-burner is under determinative control, and which is restricted to be within the temperature limit that the turbine blading will withstand.

The turbine section Z includes the turbine wheel 35 and tail pipe 40 within which continued primary or secondary burning is efficiently accomplished. As shown, the blading of turbine wheel 35 forms an annular continuation of the nozzle chamber 25 for the axial flow of working fluid therethrough. In accordance with this invention, the blades 36 are of the impulse type by which velocity is decreased in order to absorb energy, while pressure is maintained. Thus, mv^2 , is substantially greater than mv'^2 , while P_2 substantially equals P_1 . Consequently, the efficient burning pressure at the nozzle-burner discharge is maintained immediately rearward of the turbine wheel 35 for the advantageous sec-

ondary burning of fuel. In practice, complete primary burning within the axial confines of chamber 25 may be preferred, however, with the application of coolant 24 continued primary burning and/or the completion thereof, from chamber 25, can occur as the working fluid passes through the turbine wheel 35, and said continued burning is supported by the pressure value $P_2 = P_1$. As shown, secondary burner injectors 37 are provided immediately rearward of the turbine wheel 35 and in the efficient pressure zone $P_2 = P_1$ of the tail pipe 40. The divergent annulus of the tail pipe surrounding the tail cone 41 provides for the further expansion of secondary burning fuel, and with proper design, an efficient combustion pressure is maintained and a continued drop in pressure permitted thereafter for exhaust of working fluid into the atmosphere.

In accordance with this invention, the change in direction of working fluid as caused by reaction thereof through the impulse turbine blading subtracts energy from the axial flow in proportion to the power provided for the compressor and auxiliary operation as compared with the total energy of the working fluid delivered by the nozzle-burner. To this proportionate extent, therefore, the aircraft sees a reduced thrust as a result of the lateral (helical) deflection of the working fluid leaving the turbine blades 36. The velocity at P_2 is also commensurately reduced. However, this thrust is but temporarily reduced since it is regained by stator blades 38 immediately rearward of turbine blades 36 and that redirect the working fluid to flow axially and to the end that the total energy (momentum) remaining in the working fluid is seen by the aircraft as propulsive thrust. Therefore, it will be seen that there is the conservation of both momentum and pressure for the support of efficient continued burning and/or secondary burning for the increased thrust afforded thereby and which is determinative of the ultimate thrust to be developed by the engine.

Having described only a typical preferred form and application of my invention, I do not wish to be limited or restricted to the specific details herein set forth, but wish to reserve to myself any modifications or variations that may appear to those skilled in the art.

Having described my invention, I claim:

1. A moderate thrust producing gas-turbine including; a compressor section having a working fluid inlet and means discharging compressed working fluid axially at a pressure adapted to support combustion, a nozzle-burner section receiving the axial discharge from said compressor means and comprised of a rearwardly divergent passage conducting the working fluid and with its nozzle area greater than its reception area from the compressor section and having intermittently explosive combustion means for expansion and axial velocity increase of said working fluid, and a turbine section receiving the working fluid from the nozzle-burner section at said axial velocity increase and having a turbine with energy absorbing velocity decreasing and pressure conserving blading driving said compressor and discharging remaining working fluid axially rearward as propulsive thrust.

2. A thrust producing gas-turbine as set forth in claim 1, wherein the combustion means comprises injection and intermittent ignition means charging fuel into the nozzle-burner for the explosive and rearwardly focused combustion thereof.

3. A thrust producing gas-turbine as set forth in claim 1, wherein the nozzle-burner section includes a diffuser ring within said rearwardly divergent passage and stratifying the working fluid into separate layers for combustion and cooling thereof respectively.

4. A thrust producing gas-turbine as set forth in claim 1, wherein the nozzle-burner section includes spaced diffuser rings within said rearwardly divergent passage and stratifying the working fluid into spaced layers for separate combustion with a coolant layer therebetween.

5. A thrust producing gas-turbine as set forth in claim 1, wherein the combustion means comprises intermittent injection means charging the fuel and an axial spaced ignitor means for the explosive combustion thereof.

6. A thrust producing gas-turbine as set forth in claim 1, wherein the combustion means comprises intermittent injection means charging the fuel and a series of axially spaced ignitor means for the progressive explosive combustion thereof.

7. A thrust producing gas-turbine as set forth in claim 1, wherein the nozzle-burner section has concentrically spaced diffuser rings disposed therein stratifying the working fluid into spaced layers for separating combustion with a coolant layer therebetween, and wherein intermittent injection means introduces fuel into said spaced layers and axially spaced ignitors combust the explosive charges for rearward acceleration and comigning with said coolant layer.

8. A high thrust producing gas-turbine including; a compressor section having a working fluid inlet and means discharging compressed working fluid axially at a pressure adapted to support primary combustion, a nozzle-burner section receiving the axial discharge from said compressor means and comprised of a rearwardly divergent passage conducting the working fluid and with its nozzle area greater than its reception area from the compressor section and having a primary combustion means for expansion and velocity increase of said working fluid, a turbine section receiving the working fluid from the nozzle-burner section at said axial velocity increase and having a turbine with energy absorbing velocity decreasing and pressure conserving rotor and stator blading driving said compressor and for maintaining working fluid pressure adapted to support secondary combustion axially rearward thereof, and secondary combustion means for the further expansion and velocity increase of said working fluid discharging as propulsive thrust.

9. The high thrust producing gas-turbine as set forth in claim 8, wherein the secondary combustion means comprises fuel injection means charging fuel into the working fluid rearward of said turbine blading.

10. The high thrust producing gas-turbine as set forth in claim 8, wherein the secondary combustion means comprises fuel injection and ignition means charging fuel into the working fluid rearward of said turbine blading.

11. The high thrust producing gas-turbine as set forth in claim 8, wherein the turbine section rotor blading is of impulse configuration for the conservation of pressure therethrough.

12. The high thrust producing gas-turbine as set forth in claim 8, wherein the turbine section stator blading is of impulse configuration for the conservation of pressure therethrough.

13. The high thrust producing gas-turbine as set forth in claim 8, wherein the turbine section rotor blading and stator blading rearward thereof are of impulse configuration for the conservation of pressure therethrough.

14. The high thrust producing gas-turbine as set forth in claim 8, wherein the turbine section stator blading is of impulse configuration for the conservation of pressure therethrough, and wherein the secondary combustion means comprises fuel injection and ignition means charging fuel into the pressure conserved area of the working fluid.

15. The high thrust producing gas-turbine as set forth in claim 8, wherein the turbine section rotor blading and stator blading rearward thereof are of impulse configuration for the conservation of pressure therethrough, and wherein the secondary combustion means comprises fuel injector and ignition means charging fuel into the pressure conserved area of the working fluid.

16. A high thrust producing gas-turbine including; a compressor section having a working fluid inlet and means discharging compressed working fluid axially at a pressure adapted to support primary combustion, a nozzle-burner section receiving the axial discharge from said compressor means and comprised of a rearwardly divergent passage conducting the working fluid and with its nozzle area greater than its reception area from the compressor section and having intermittently explosive primary combustion means for expansion and axial velocity increase of said working fluid, a turbine section receiving the working fluid from the nozzle-burner section at said axial velocity increase and having a turbine with energy absorbing velocity decreasing and pressure conserving blading driving said compressor and for maintaining working fluid pressure adapted to support secondary combustion axially rearward thereof, and secondary combustion means for the further expansion and velocity increase of said working fluid discharging as propulsive thrust.

17. The high thrust producing gas-turbine as set forth in claim 16, wherein the nozzle-burner section includes a diffuser ring stratifying the working fluid into separate layers for combustion and cooling thereof respectively.

18. The high thrust producing gas-turbine as set forth in claim 16, wherein the nozzle-burner section includes spaced diffuser rings stratifying the working fluid into spaced layers for separate combustion with a coolant layer therebetween.
